FOREIGN PATENT DOCUMENTS

WO 2018068139 A1 4/2018

Primary Examiner — Shannon W Morgan*Assistant Examiner* — Adedoyin Taiwo Odeyale(74) *Attorney, Agent, or Firm* — Polson Intellectual Property Law P.C.; Margaret Polson; Christopher Sylvain(57) **CLAIM**

The ornamental design for a bed fan, as shown and described.

DESCRIPTION

FIG. 1 is a top front perspective view of a bed fan;

FIG. 2 is a bottom rear perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

Broken lines and adjacent unshaded portions of the bed fan form no part of the claimed design.

1 Claim, 6 Drawing Sheets(56)
